UNITED STATES PATENT OFFICE

EDWARD L. ILSON, OF PATCHOGUE, NEW YORK

DESIGN FOR A STORE FRONT

Application filed May 28, 1929. Serial No. 31,442. Term of patent 7 years.

To all whom it may concern:

Be it known that I, EDWARD L. ILSON, a citizen of the United States of America, residing at Patchogue, county of Suffolk, State of New York, have invented a new, original, and ornamental Design for a Store Front, of which the following is a specification.

Fig. 1 is a perspective view of a store front, showing my new design.

Fig. 2 is a diagrammatic top plan view of the design.

I claim:

The ornamental design for a store front as shown.

Dated at New York, this 23d day of May, 1929.

EDWARD L. ILSON.
